UNITED STATES PATENT OFFICE

2,431,225

METHOD OF FINISHING FLOORING AND
OTHER WOOD

William N. Belk, Rockford, Ill.

Original application September 27, 1943, Serial
No. 504,077. Divided and this application
March 29, 1944, Serial No. 528,601

2 Claims. (Cl. 117—59)

1

This application is a division of my co-pending application, Serial No. 504,077, filed September 27, 1943.

This invention relates to a novel method of finishing flooring and other wood so that the flooring, for example, is ready for use, the wood being dipped for moisture-proofing, termite and powder post beetle proofing, as well as resistance to fungus, and being thereafter dried, waxed, buffed and polished on all sides. The treatment is applicable to oak, maple, beech, pecan and hickory flooring, and all soft wood lumber in flooring, ceiling, drop siding, finish and plywoods.

The salient feature of my invention lies in the fact that the intake leg of the generally U-shaped machine includes an immersion tank into which the pieces are discharged directly from a sander or sanders and are then fed onto a conveyor for passage endwise through a wiper for removal of excess liquid that is conducted back to the tank. In that way the pieces have the dust rinsed off in the immersion and whatever small amount of dust might still adhere after the immersion is more or less certain of removal in the passage of the pieces between the brushes of the wiper. The pieces, therefore, emerge from the wiper in the best possible condition for drying, there being no surface dirt or dust and no surplus liquid that would interfere with even drying.

Another important feature of my invention lies in the fact that the brushes provided in the wiper unit operate on all four sides so as to remove any dirt or dust that might still adhere after the immersion, and make certain that no liquid is left in the grooves or along the tongues which would interfere with thorough drying of the wood before it reaches the waxing and polishing unit, all excess liquid, as stated before, being conducted back to the immersion tank so that there is no waste.

In the generally U-shaped machine operated in accordance with my improved method, the cross portion includes the drier, and is wide enough to permit the feeding of pieces sidewise therethrough, as distinguished from the endwise feeding through driers in earlier machines, and in that way the whole piece is subjected to drying simultaneously and there is eliminated any likelihood of breakage of lamps. The outgoing leg of the machine has a conveyor that feeds the dried pieces endwise through a waxing and polishing unit.

The invention is illustrated in the accompanying drawings, in which—

Fig. 1 is a plan view of a machine operating in accordance with my improved method;

Fig. 2 is a vertical section through the immersion tank, taken on the line 2—2 of Fig. 1;

Fig. 3 is a vertical section through the drier, taken on the line 3—3 of Fig. 1, and

2

Figs. 4 and 5 are a plan view and side view of the wiper unit.

The same reference numerals are applied to corresponding parts throughout the views.

Referring first to Fig. 1, the reference numeral 10 designates the immersion tank forming a portion of the intake leg of the generally U-shaped machine, and at 11 is indicated a sander from which the pieces 12 of wood flooring, or other lumber, are discharged into the immersion tank. Second sander is indicated in dotted lines at 11a at the opposite end of the tank, inasmuch as the pieces to be treated may be discharged into the tank from both ends, machines of the present type having been built and satisfactorily operated upon as much as four thousand feet of wood flooring per hour. Incidentally, these machines require only eight men per machine, whereas the previous in-line type of wood finishing machines usually required about sixteen men and the production on those machines was usually only about fifteen hundred feet per hour. The pieces 12 are completely immersed in the bath 13, and are carried upwardly from the bath on a conveyor 14 and deposited on a conveyor 15 for passage through the wiper unit 16 preliminary to the placing of these pieces on another conveyor 17 operating at right angles to the conveyor 15 for passage through the drier 18. A drain 19 extends from the tank 10 under the wiper unit 16 and serves to conduct back to the tank the surplus liquid removed from the pieces passing through the wiper unit, so that there is no waste. Another conveyor 20 operates at right angles to the outlet end of the conveyor 17, parallel to the conveyor 15, and conveys the pieces endwise through waxing and polishing unit 21. Finally the finished pieces, waxed and polished ready for use, are received on a table 22 at the end of the outgoing leg of the generally U-shaped machine. The U-shape is of considerable advantage, not only from the standpoint that it permits installation of the machine in a building of ordinary size and proportions but also because with the compact arrangement about half as many men are needed in the operation of the machine. For example, the in-line design of previous machines required a building 500 ft. long, producing 1500 feet of finished lumber per hour with 16 men, whereas the present machine has been installed in a 34 ft. by 64 ft. building and produced 4000 feet of finished lumber per hour with only 8 men.

The immersion tank 10, as illustrated in Fig. 2, has a generally rectangular sump portion 23, on one side of which is a vertical wall 24 and a chute 25 extending from the top thereof the full length of the tank to cause the pieces to slide down into the preservative solution and be thoroughly wetted. An inclined drain board 26 projects up-

wardly at a small angle from the bottom of the sump 23 on the opposite side from the wall 24 to a point beyond the conveyor 15, where a vertical side wall 27 is provided, which with the opposed end walls 28 and 29 completes the tank. The conveyor 14 has sprockets for driving the same mounted on longitudinally extending shafts 30 and 31, one of which is suitably driven to cause the conveyor to run in the direction indicated by the arrows for continuously feeding the wetted pieces 12 from the bath 13 onto the conveyor 15, in the manner indicated in Figs. 1 and 2. The drive means has not been shown, but it will be understood that the conveyor 14 will operate continuously throughout the operation of the rest of the machine. Most of the excess liquid on the pieces is drained from them as they are carried up on the conveyor chains 14 and when they land on the conveyor 15. A longitudinally extending strip 32 is provided between the discharge end of the conveyor 14 and the conveyor 15, as shown in Fig. 2, to guide the pieces onto the conveyor 15 and eliminate likelihood of pieces dropping between the conveyors and being returned to the bath. The pieces will be stacked on the conveyor 15 by an operator in the event they are fed to the conveyor faster than they are removed by the conveyor 15 and passed through the wiper unit 16. This end 33 of the tank 10 in which the conveyor 15 operates has for that reason been called the magazine. The conveyor 15 continuously feeds the lowermost pieces from the stack in the magazine into the wiper unit 16 and, as stated before, a drain 19 projecting from the end of the tank 10 under the wiper unit returns to the tank whatever excess liquid is removed from the pieces in their passage through the wiper unit, thus eliminating any waste of preservative solution and at the same time insuring uniformly wetted pieces being fed to the drier, so that there will be no difficulty in drying the pieces uniformly and completely preparatory to the final waxing and polishing. In passing, it should be clear that the complete immersion of the pieces in the preservative solution is far more beneficial than merely applying by spray nozzles some of this solution to the top surface, as was done in earlier machines. This treatment gives 100% protection, whereas the other treatment gave substantially less than 50% protection. Furthermore, the complete immersion of the pieces right after they leave the sander is of advantage in rinsing the sander dust off, so that no intermediate step of brushing or otherwise cleaning is necessary, and if any dust still adheres when the wetted pieces enter the wiper unit, that small amount is certain of removal in passing through the brushes in the wiper unit at the same time the remaining excess liquid is removed.

The wiper unit 16 is also known as the brushing unit, inasmuch as the wiping is done with brushes. There are four brushes 34, 35, 36, and 37. The brushes 34 and 35 are horizontally disposed above and below the path of travel of the lumber, in a space between the conveyor 15 and its companion conveyor 15a, in order to brush off the top and bottom surfaces of the pieces as they pass through. The brushes 36 and 37 are on vertical axes and are disposed adjacent the brushes 34 and 35 on opposite sides of the line of travel, so that one brush will work in the grooved portion and the other on the tongued portion of a piece of flooring, for example. The brushes 34 and 35 have their bearings vertically adjustable on the upright frame members 38 to suit different thick-

nesses of work and to compensate for wear. Sheet metal shields 40 and 41 are provided over the brush 34 and around the outer sides of the brushes 36 and 37, to catch whatever liquid might otherwise be sprayed from these brushes in the operation of the machine and discharge it into the drain 19 disposed therebeneath.

Belt and pulley drives are illustrated for the four brushes, and also a chain and sprocket drive 10 42 for transmitting drive from the incoming conveyor 15 to the outgoing conveyor 15a. Feed rollers 43 disposed above the end portion of the conveyor 15 serve to reduce slippage, and they with the conveyor 15 more or less positively feed the pieces through between the brushes. Another feed roll 44 cooperates with the adjacent end portion of the conveyor 15a to assist in the feeding through of the work. It should be evident from this description that the wetted pieces leaving the wiper unit 16 will not only be thoroughly cleaned by reason of their passage between the brushes, but all surplus liquid will be removed and returned to the sump 23 by the drain 19.

An operator stationed at the far end of the conveyor 15a, remote from the wiper unit 16, 25 removes the pieces 12 and places them on the conveyor 17 for passage sidewise through the drier 18, as indicated in Fig. 1. A hood 45 together with side walls 46 is adjustable vertically 30 with respect to frame members 47, as by means of jack screws 48, to adjust a horizontal bank of infra-red lamps 49 vertically with respect to the conveyor 17, to suit different thicknesses of work and also to insure correct drying without danger 35 of scorching, bearing in mind the length of travel of the pieces through the drier and, of course, the speed of travel as well as the drying characteristics of the preservative solution used. The fact that the pieces 12 are fed sidewise 40 through the drier is important, because it eliminates a serious objection to the in-line design of machine, namely, that a piece getting askew when fed endwise through the drier was apt to break a whole row or more of expensive infra-red lamps 45 in the positive feeding of the work through the drier, before an operator could do anything about it. Such breakage is positively prevented with the present design, and each piece is simultaneously subjected to drying throughout the full 50 length thereof, so that the drying time between the entrance and exit ends is more easily checked and adjustments can more readily be made than where the pieces are fed through endwise.

The pieces are hot when they leave the drier and, therefore, cannot be handled. For that reason the conveyor 20, disposed at right angles to the conveyor 17, is on a lower level, as indicated in Fig. 3, and the dried pieces drop off the conveyor 17 onto the conveyor 20 for passage endwise 60 through the waxing and polishing unit 21. The conveyor 20 extends into the feed-in end of the unit 21 for the waxing and polishing of the pieces in the manner fully illustrated and described in the parent application, the finished pieces being 65 conveyed from the machine on the conveyor 20a onto the table 22.

It is believed the foregoing description conveys a good understanding of the objects and advantages of my invention. The appended claims have been drawn to cover all legitimate modifications and adaptations.

I claim:

1. The method of finishing lumber, such as flooring, which includes the steps of sanding the previously dried pieces, then immersing the pieces

in a preservative solution whereby to rinse off sander dust at the same time that all surfaces are coated for protection of the wood, then removing excess liquid from the surfaces and also any dust or dirt still adhering to the surfaces after the immersion by passage of the pieces endwise through a wiper, and thereafter drying the pieces by passage sidewise through a heating oven that is heated by a bank of infra-red lamps supported in a substantially horizontal plane above the surface of the wood.

2. The method of finishing lumber, such as flooring, which includes the steps of sanding the previously dried pieces, then immersing the pieces in a preservative solution whereby to rinse off sander dust at the same time that all surfaces are coated for protection of the wood, then removing excess liquid from the surfaces and also any dust or dirt still adhering to the surfaces

10

after the immersion by passage of the pieces endwise through a wiper, then drying the pieces by passage sidewise through a drier that is heated by lamps disposed in a substantially horizontal plane above the surface of the wood, and finally waxing and polishing the pieces by passage endwise through a waxing and polishing unit.
